UNITED STATES PATENT OFFICE.

ABRAHAM HERMAN, OF LOS ANGELES, CALIFORNIA.

SKYLIGHT ADJUSTER.

Application filed November 20, 1924. Serial No. 751,087.

This invention relates to improvements in skylight adjusters.

It is an object of this invention to provide a skylight adjuster which may raise or lower a skylight by actuation at a remote location of a flexible element.

A further object of this invention is to provide means for raising and lowering a skylight, and also, to provide a device which will prevent the skylight from being thrown open by the wind when partially open.

With the foregoing and other objects in view which will be made manifest in the following detailed description and pointed out in the appended claims, reference is had to the accompanying drawings for an illustrative embodiment of the invention, wherein:

Figure 1 is a perspective view of a skylight to which the improved skylight adjuster has been applied;

Fig. 2 is a side elevation of the skylight adjuster, parts being broken away and shown in vertical section; and

Fig. 3 is a horizontal section taken substantially on the line 3—3 of Fig. 2.

Referring to the accompanying drawings wherein similar reference characters designate similar parts throughout, the improved skylight adjuster consists of a support 10 which is adapted to be mounted upon the inside of the frame F, upon which is hinged or otherwise positioned the skylight S. A pair of lugs 11 project forwardly from the face of the support 10, and a collar 12 carrying a projection 13 is pivoted between the lugs 11 by means of a bolt 14. A jack screw 15 is slidable within the collar 12 and has threaded thereon a beveled pinion 16 which normally rests upon the top of the collar 12. A spindle 17 is formed integral with, or otherwise secured to, the collar 12, and a beveled gear 18 is rotatably mounted thereon. This beveled gear meshes with the beveled pinion 16 and upon rotation produces rotation of the pinion 16 and thereby produces upward or downward movement of the jack screw 15.

A suitable sprocket 19 may be formed integral with the beveled gear 18, or be otherwise secured thereto, and a flexible element, such as a sprocket chain 20, is adapted to pass thereover, so that a downward pull of either of the depending strands or lengths of chain will cause rotation of the beveled gear 18.

The lower end of the jack screw 15 is pro-

vided with a suitable enlargement 21 which prevents or limits the upward movement of the jack screw 15 through the collar 12. The upper end of the jack screw 15 is provided with a head 22 extending through a securing member 23. The head 22 is loosely mounted in the securing member 23 so that the jack screw 15 has a limited pivotal movement with respect to the securing member 23.

As a means for preventing the skylight S from being thrown open by the wind, the beveled gear 18 carries a flange 24, which passes over the top of the beveled pinion 16 and limits the upward movement of the beveled pinion 16 with the jack screw 15 so that the pinion and the gear are always kept in engagement.

A plate 25 is carried upon the spindle 17 and has its edges bent over the sprocket 19, as indicated at 26, and is also provided with an in-turned flange 27. The turned-over edges 26 and the flange 27 serve to maintain the sprocket chain 20 upon the sprocket 19 so that although the depending lengths of the chain 20 may not be pulled vertically downward, the flange 27 and the plate 25 prevent the chain from slipping off the sprocket 19. The turned-over edges 26 and the flange 27 are cut away adjacent the bottom of the plate 25 to permit the chain 20 to pass therethrough. As the skylight is raised, the jack screw 15 will be swung slightly from its vertical position, and because of the pivoted relation between the collar 12 and the support 10, the jack screw 15 may assume any position necessary. Because of this swinging movement, it is essential that the upper end of the jack screw 15 have a limited pivotal relation with respect to the skylight S.

It will be understood that various changes in the details of construction may be made without departing from the spirit or scope of the invention as defined by the appended claims.

I claim:

1. A skylight adjuster comprising a support, a collar pivoted to said support, a jack screw slidable within said collar, a beveled pinion threaded on to said jack screw and normally resting upon said collar, a beveled gear rotatably mounted upon said collar and meshing with said pinion, a flange carried by said beveled gear and passing over said pinion, a sprocket secured to said beveled gear, a chain engaging said sprocket

- adapted to produce rotation thereof, means for preventing disengagement of said chain from said sprocket, and means for pivotally securing said jack screw to a skylight.
5. 2. A skylight adjuster comprising a bracket, a pair of spaced lugs provided upon said bracket, a collar having a projection disposed between said lugs, a bolt passing through said lugs and projection so as to pivot said collar to said bracket, a jack screw slideable within said collar, a beveled pinion threaded onto said jack screw, a spindle upon the collar, a beveled gear rotatable upon the spindle and meshing with said pinion, and means for rotating said beveled gear.
10. 3. A skylight adjuster comprising a bracket, a pair of spaced lugs provided upon said bracket, a collar having a projection disposed between said lugs, a bolt passing through said lugs and projection so as to pivot said collar to said bracket, a jack screw slideable within said collar, a beveled pinion threaded onto said jack screw, a spindle upon the collar, a beveled gear rotatable upon the spindle and meshing with said pinion, and means for preventing disengagement between the sprocket and chain.
15. 4. A skylight adjuster comprising a bracket, a pair of spaced lugs provided upon said bracket, a collar having a projection disposed between said lugs, a bolt passing through said lugs and projection so as to pivot said collar to said bracket, a jack screw slideable within said collar, a beveled pinion threaded onto said jack screw, a spindle upon the collar, a beveled gear rotatable upon the spindle and meshing with said pinion, means including a sprocket and a chain for rotating said beveled gear, and means for maintaining said beveled pinion adjacent said collar.

In testimony whereof I have signed my name to this specification.

ABRAHAM HERMAN.
